UNITED STATES PATENT OFFICE.

OTTO A. KREUTZBERG, OF LAKE BLUFF, ILLINOIS, ASSIGNOR TO BLANTON-KREUTZBERG COMPANY, OF CHICAGO, ILLINOIS, A CORPORATION OF ILLINOIS.

PULVERIZING APPARATUS.

Application filed March 17, 1921. Serial No. 452,986.

To all whom it may concern:

Be it known that I, OTTO A. KREUTZBERG, a citizen of the United States, residing at Lake Bluff, in the county of Lake and State 5 of Illinois, have invented certain new and useful Improvements in Pulverizing Apparatus, of which the following is a specification, reference being had to the accompanying drawings, forming a part thereof.

10 The purpose of this invention is to provide an improved construction for pulverizing hard material adapted in one of its forms for separating the material according to fineness, so that only that which is pulverized to a desired degree shall be delivered, the remainder being returned for further treatment. It consists in the elements and 15 features of construction shown and described as indicated in the claims.

20 In the drawings:

Figure 1 is a vertical axial section of a structure embodying this invention.

Figure 2 is a detail elevation of a portion 25 of the structure shown in Figure 1, a portion of the casing being broken away, said shaft and bearings shown in section.

Figure 3 is a detail section at the line, 3—3, on Figure 1.

Figure 4 is a section at the line, 4—4, on 30 Figure 3.

Figure 5 is a detailed section at the line, 5—5, on Figure 2.

Figure 6 is an axial section of one of the 35 two rolls which alternate around the table with those shown in Figure 1, showing the differing order of assemblage of the roll sections on the axle.

Figure 7 is a section at the line, 7—7, on Figure 1.

40 The structure shown in the drawings comprises a support, 1, upon which there is mounted for rotation about a vertical axis a table, 2, having its upper face dished for lodgment thereon of pulverizing rolls, 3, 45 which are mounted for rotation upon axis, 4, hinged upon brackets, 5, mounted upon the support, the position of the hinge and the form of the rolls being adapted to the slope of the dished table so that the rolls 50 lodge along their entire length upon the table and are rotated about their own axes as the table revolves about its axis by frictional engagement of the rolls with the table and with the material thereon.

55 While, in the main, the pressure for pul-

verizing is derived by gravity from the weight of the rolls, it is desirable to provide additional means which may be modified to vary the pressure according to the character of the material, and for this purpose each of the roller axles, 4, is terminated by a T-fitting, 4^a, which may be considered in general as a part of the axle, the cross of the T being fitted between the lugs, 5^a, of the bearing bracket, 5, while from the cross of the T there is extended a second lever arm, 4^b, approximately at right angles to the roller shaft, 4. Upon the bracket, 5, there is formed at the lower part in the angle between the vertical and horizontal flanges of the web of the bracket, a boss, 5^c, whose tablet faces the downwardly-projecting end of the lever arm, 4^b; and between said boss and said lever arm there is interposed a spring, 19, at whose outer end there is lodged a block, 19^a; and through the end of the lever arm, 4^b, there is set a tension screw, 21, which operates in the head of the block, 19^a, and is provided with a jam nut, 21^a, to secure it as set in the lever arm, 4^b, for adjusting the tension of the spring to vary the pressure of the roller.

The material to be treated is designed to be delivered to a conduit comprising a terminal duct, 6, which delivers it at the center of the table over an upraised central portion or tablet, 7, thereof, by which it is initially spread outward, the upraise being sloping at its margin so as to lodge the material upon the table proper at a little distance from the center of the table, whereby the centrifugal tendency resulting from the rotation of the table, operates to move it further outward and enter it between and under the rolls as the latter roll upon the table. Preferably the form of the upraise, 7, is as shown, comprising a central flat tablet portion, 7^a, and marginal sloping portions, 7^b; and the diameter of said flat tablet portion is greater than the diameter of the discharge mouth of the conduit pipe, 6, by an amount such that the angle of slope of the cone frustum whose larger base has the diameter of said flat portion and whose smaller base has the diameter of the mouth of the pipe, 6, and whose height is the distance to which the mouth of the pipe, 6, will be raised above the flat portion for maximum discharge of material, shall be substantially the angle of repose of

the material. The purpose of this specific form of the upraise, 7, is that thereby when the rotation of the table is arrested, the material which is being delivered through the pipe, 6, automatically becomes a means of closure of the delivery aperture between the end of the pipe, 6, and the tablet, the material which is being delivered, not being carried away by the centrifugal force, ac-
10 cumulating in a pipe upon the flat tablet which will not decrease nor flow away, be-
cause of the angle of its slope being, as indi-
cated, the angle of repose of the material.

The centrifugal action of the material re-
15 tarded by gravity by the upward outward slope of the table when this is tapered, causes the material to advance outwardly along the table under the rolls slowly as the table revolves, following in fact a spiral path, and being repeatedly crushed and ground by the rolls, until it emerges at the circumference of the table, ground or pul-
20 verized to the degree of fineness desired. The rate of its advance outward from the center of the table to the circumference and thereby the rate of exposure to the pulv-
25 erizing action of the rolls on the table may be regulated by the speed of rotation of the table, said speed being adapted to the char-
30 acter of material, so that it will be kept within the operation of the device long enough according to experience, to reduce the most refractory parts to the desired de-
35 gree of fineness by the time it is advanced to the circumference of the table.

The support, 1, is apertured at an annular area situated under the outer circumference of the table, as seen at 1^a, so that the material delivered over the outer margin of the table, through the annular throatway, 1^x, formed between the margin of the table and a throttling member, 1^b, mounted on the casing, 12, passes through said apertures, 1^a; and from the lower side of the support there
40 is suspended a funnel or gathering casing, 14, encompassing the annular apertured area of the support, so that the material delivered through said apertures is received by the casing and gathered for discharge at its
45 discharge mouth, 14^a. A cylindrical casing member, 12, encloses the table and the rolls above the support and outside the circle of the apertures, 1^a, said casing being notched at its upper edge at 12^a, to accommodate the
50 axles of the rolls, permitting the rolls to be swung out of the casing for attention or for clearing the table. From the top of the cy-
55 lindrical casing member, 12, the enclosure is continued upward for discharge of the pul-
60 verized material when provision is made for separation by air current, as is one mode of use of the structure, as hereinafter more particularly explained; said extended cas-
65 ing consisting of interlocking sectors, 12^b, one sector for each roll constituting a con-

tracted neck portion and a frusto-conical funnel, 12^y, extending upward from the upper narrower end of said neck portion, widening to a diameter somewhat greater than the diameter of the casing member, 12, the 70 casing being thence continued upward in the cylindrical portion, 12^z, which is provided with a central discharge hereinafter de-
scribed. Suspended centrally within the funnel portion, 12^y by means of bracket arms, 22, extended from the part, 12^y, is the receiving funnel proper, 17, into which the material to be treated is conducted by a feed pipe, 17^a, which leads in through the cylindrical upper member, 12^z, as seen in 80 Figure 1. The lower end, 17, is connected for discharge with the two-part telescoping delivery tube comprising the parts, 18 and 6, the former carried fixedly on the lower end of the funnel, 17, and the latter telescoping 85 outside of said former tube, 18 (whereby its discharge mouth is made adjustable, as above indicated, with respect to the central tablet, 7^a, of the upraise member, 7). And for this adjustment, said telescoping mem-
90 ber, 6, has two pairs of links, one pair at each side of said member, 6, pivoted there-
to upon the same pivot, 19^b, the two links of each pair diverging from their said pivot upwardly, and being connected to nuts, 19^a, mounted for travel in and out on a screw shaft, 20, said shaft having for said nuts, re-
spectively, right-hand and left-hand threads as shown at 20^a, 20^b. Said shaft is jour-
naled in a fitting, 21, which serves to connect the telescoping pipe members with the funnel, 17, the nuts being on the shaft outside of its journal bearings shown at 20^c, and the shaft extending out through the outer funnel member, 12^y, of the casing for operation 105 from the exterior for adjusting the telescoping pipe terminal, 6, as described.

22 is a square rod which is steadied at its upper end in a bearing on the shaft, 20, and at the lower end is mounted to rotate with the shaft, 2^a. Its function is to cause the breaking up of any exceptionally large fragments fed into the delivery tube and to prevent bridging of the material in the tube by agitating it and breaking up the larger 115 pieces by the encounter and engagement between the corners of said rod, 22, and the tube wall.

When the pulverized material is not to be separated or graded but is to be kept on the 120 table until pulverized to a desired degree of fineness and then delivered over the margin of the table through the throatway, 1^x, and down through the apertures, 1^a, as described, the retention of the material on the table 125 until it is thus pulverized is insured by means of a discharge-controlling ring, 25, cylindrical in form, having its lower edge overhanging the outer margin of the table 130 and adapted to be adjusted vertically to pro-

duce a crevice of any desired width between its lower edge and said table margin, so that any material which reaches the margin of the table, having passed the rolls too large to pass the crevice, will be stopped by the ring and thereby thrown back between the rolls to be further operated upon by them until crushed to the desired degree of fineness. And to ensure such return of the 5 sufficiently reduced fragments there is desirably appended to the ring, 25, at one point in its circumference between two consecutive rolls, an inwardly curved wiper, 25^g, (see Figures 3 and 4) which pushes the 10 larger material back from the margin of the table as it revolves past said wiper.

For purpose of adjusting this discharge-controlling ring, it is carried by a plurality of stems, 25^a, preferably one for each between the rolls, said stems projecting out through the casing member, 12, which is slotted vertically for that purpose, and outside the casing said stems are engaged in eye-bolts, 26, which in turn are engaged 25 in brackets, 27, secured upon the outside of said casing member, 12, nuts, 26^a, 26^b, on said eye-bolts above and below the engagement of stems of said bolts with said brackets, serving to adjust and secure at 30 adjusted position said discharge-controlling ring, 25. As shown, said discharge controlling ring consists of a lower and upper part, the lower part being heavier and thicker as is necessary for insuring its fixed- 35 ness of form, and affording anchorage for the supporting stems mentioned, the upper part being of thin material serving to extend the ring up past the height of the rolls, and being notched to accommodate the 40 roll shafts for their swinging in and out as above described, and for their slight rise and fall in the operation of crushing material on the table. The upper part, 25^b, serves and is required for arresting and re- 45 turning to the table flying fragments of the material undergoing pulverizing.

The means of rotating the table consists of a gear, 8^a, mounted upon the stem or spindle, 2^a, of the table, said gear being 50 driven by a pinion, 8, mounted upon a driving shaft, 9. The entire driving train is enclosed in a housing, 10, suspended from the lower side of the support, 1, having a step bearing, 10^a, at the lower end for the 55 spindle table shaft, 2^a. The housing, 10, constitutes a grease chamber for containing lubricant for the gears; and any suitable provision is made for conducting lubricant to the several bearings. Said hous- 60 ing, it will be observed, is suspended within the funnel or gathering casing, 14, which constitutes an annular chamber around the housing, the latter serving to prevent contamination of the material by reason of the 65 grease in the housing, and also to prevent

the pulverized material getting into the gears or bearings.

As above indicated, a very desirable mode of use of this structure consists in causing a current of air to pass through it from below the table up around the circumference thereof, thereby traversing the film of material delivered over the circumference of the tablet, such air current being graduated as to its velocity so as to pick up the 70 material thus delivered and carry it up above the rolls to a point where the air velocity is less, where portions of material which are too coarse to be held suspended by the air current of the first mentioned 75 velocity selected, will be dropped and will fall again between the rolls onto the tablet for further crushing and grinding, while the finer portions which can be lifted by the air current of a given velocity are carried with said air current out through the 80 casing members to the point of accumulation and storage. The path of the material thus lifted is through the annular throat between the frusto-conical casing member 85 or funnel, 12^y, and the funnel, 17. The material, however, does not escape by passing directly upward from the said annular discharge from between the two funnels. On the contrary, the cylindrical member, 90 12^p, is closed at the top over an outer circumferential portion, the suction or exhaust connection being made at the center of the top web, 12^m, of said upper cylindrical portion, 12^z, as seen at 13; and there is projecting downward from said web within the 95 said cylindrical casing member, 12^p, a cylindrical flange, 12ⁿ, whose diameter is substantially twice that of the exhaust connection, 13: and telescoping outside of said 100 flange 12ⁿ, is an extension member, 12^p, which may be adjusted on said flange, 12ⁿ, by means of an operating arm or stem, 12^r, extended upward through the top web, 12^m, and accessible exteriorly for such adjustment of the extension, 12^p. The intention of 105 this adjustable extension in connection with the entire construction of which it is a part, is to enable the operator to vary the annular air gap between the lower end of 110 said extension, 12^p, and the funnel, 17, below it to cause the velocity of the air to be varied according to the degree of fineness to which it is desired to reduce the material 115 before permitting it to leave the apparatus. For it will be understood that as the air current passing up through the annular opening between the upper margin of the funnel, 17, and the frusto-conical case member, 12^y, is reversed and deflected in the 120 annular space outside of the flange, 12ⁿ, and the extension, 12^p, in the cylindrical case member, 12^z, and returns down around the lower end of the extension, 12^p, the larger 125 and coarser material will be thrown out 130

tangentially to the current as it is reversed around the lower margin of the part, 12^p, and enters upwardly into said pipe, said coarser material being thrown down into the funnel, 17, and caused to pass again over the table under the rolls for further crushing. And also, any material too coarse to be carried by a current having the velocity which is controlled by the area of the annular opening between the lower end of the part, 12^p, and the funnel, 17, but which is not thrown out tangentially as stated, in the reversal of the direction of the air current as it turns upward, will be dropped by the air current while the current is moving upward through the parts, 12^p and 12ⁿ, to the final outlet at 13, and falling into the funnel, will be carried again over the table for further reduction.

It will be understood upon consideration of the drawing, that the maximum air velocity would be experienced at the margin of the table, the total area of the throatway afforded at 1^b, being less than the cross-section of the air current at any other part of the path, and that consequently much material will be lifted at that point which will be subsequently dropped after the air current has been deflected inward over the rolls and before it has passed out between the two funnels, 17 and 12^y; and that there may be repeated returns before the final emergence of the material reduced to the desired degree of fineness. The vertical adjustability of the throttle member, 1^b, provides for varying the cross section and maximum velocity of the air current at the margin of the table and thus varying the fineness of the material carried upwards by the air blast at this point. Such variation of cross section results in the downward adjustment of the throttle member, 1^b, away from the bevel of the under edge of the table as seen at 2^x, and in the upward adjustment of the throttle member away from the under bevel of the throttle itself, as seen at 1^y. The vertical adjustability of the throttle is obtained by mounting it by several stems of which one is shown in Figure 1 at 1^z, extending through vertical slots in the casing of which one is shown at 12^z, in Figure 7, nuts, 12^m, being applied on the stem outside the casing to clamp them in adjusted position.

Certain details of construction shown in the drawings require description.

It is desirable that each roll should be made of a plurality of narrow sections so as to take from the table rolling speed independently of each other, each according to the circumferential speed of the zone of the table on which it rests and rolls. And in order that this division of the rolls into sections as seen in Figure 1 may not leave untraversed zones on the table between the zones traversed by the separate sections of

the rolls, said sections, 3^x, are made as seen in Figure 1, with their table-engaging periphery, 3^m, offset from the middle of the width of the roll section, leaving a hub, 3ⁿ, projecting at one end and a central recess, 3^b, of somewhat greater diameter than the hub at the other end, the hub of one section being entered in the recess of the other section when the two sections are assembled on the shaft. By reversing the position of the sections in alternate rolls, the tracks of the sections of each roll constitute zones on the table covering the interval between and the margin at the inner or outer side beyond the zones which constitute the tracks of the next roll.

The particular construction shown, to-wit: the roll sections having each at one end a hub and at the other end a recess adapted to receive the hub; results primarily from the means adopted for protecting the journal bearings of the rolls on the axles from dust arising from the material to be treated. For this purpose the end of the axle has a cap nut, 3^w, secured onto it, closing that end of the journal bearing, and this may be further protected by a dust cap, 3^t, as seen in Figures 1 and 6. At the other end of the other roll section the protection is afforded by recessing the roll as seen at 3^p, and providing the sleeve, 3^s, which constitutes the hinged end portion of the axle, with a flange, 3^r, whose periphery has a groove to receive a packing, 3^v, which seats on the inner peripheral wall of the recess 3^p. The roll sections are extended in the hub 3ⁿ, at the end opposite that which has the recess, 3^p, and the periphery of the hub has a groove, 3^b, to receive a packing, 3^y, adapted to seat on the inner periphery of the recess, 3^b. In Figures 1 and 6, the different modes of co-operation of the recesses and hubs, flanges and packing for excluding dust, is shown in the reverse order of assembling of the two roll sections for the purpose above stated of causing the overlapping of their tracks as they roll upon the table.

To provide for swinging the rolls out of the casing for any purpose for which it may be necessary, the member, 12^y, of the casing has sliding doors, 12^x, for which retaining and guide bars, 12^s, and 12^t, are provided on the outside of said casing member around the apertures made for the exit of the rolls, said doors having operating handles, 12^k, and the neck portion, 12^l, of the casing made of separately removable sectors which are latched in place by latches, 12^u, on the lower end of the sliding doors, 12^x. To close the notches, 12^a, in which the shafts of the rolls swing, there are provided two-part slides, 31, 32, (see Fig. 2) for which slideways are provided at the lateral margins of said notches as seen at 33. These slides obviously must be adapted to rise and fall with the roll

shaft, as the rolls are lifted and fall in the passage of material under them as the table rotates; and for this purpose the two parts, 31, 32, are connected by rods, 35, extending 5 on opposite sides of the roll shaft, and through lugs, 36, on the upper part, 31; and above the lugs wing nuts, 37, are provided for securing them. When a roll is to be 10 swung out of the casing for attention, the wing nuts will be removed and the upper part, 31, of the slide will be withdrawn from the rod, 35.

Material to be pulverized is fed centrally of the table on which it migrates outwardly 15 to be crushed by the rolls. This outward movement is due to centrifugal force; and, to prevent too rapid outward movement of the material, the table is provided with an annular track which is inclined downwardly 20 at a slight angle from its periphery toward its center.

In evolving the present type of pulverizer, I found that good pulverizing, with a machine of the present type, involves the proper 25 coordination of two factors, namely, (1) rotational speed of the table, and, (2) the angle of inclination of the table.

As a result of experimentation, I have found that the best crushing action takes 30 place when a roller has a relative speed of from 700 to 1000 feet per minute with respect to a table. In other words, the relative speed of a roller and a table should be sufficiently high so that there is enough 35 energy of impact of a roller to obtain good crushing action. If a roller passes slowly over a particle to be crushed, the only force tending to produce crushing is that due to the weight of the roller; on the other hand, 40 if the roller moves with a sufficient degree of speed, it will be obvious that the kinetic energy or impact on a particle will be considerable. Another factor which assists in the pulverizing action is that the rollers have 45 a differential speed relation with respect to a table producing a grinding or attrition action with respect thereto.

With a table approximately four feet in diameter, it is necessary to drive it at about 50 70 R. P. M. in order to obtain a peripheral linear speed around 800 feet per minute. This speed being desirable from the standpoint of the best crushing impact, it was necessary to dish the table slightly in order 55 that centrifugal force might be sufficiently opposed by gravity to impede the outward movement of material so that it might be properly crushed. I have found, under the circumstances just stated, that an angle of 60 approximately 12° is sufficient for this purpose. Best grinding takes place when there is neither a clogging of the table with material due to insufficient outward movement nor too rapid outward movement which 65 would result in too small a percentage of

material being sufficiently passed over by the rolls. These conditions are satisfied by designing a table having such an angle of inclination for its speed that the angle thereof is only slightly less than what might be 70 termed the "centrifugal angle of repose" of material on the table, whereby centrifugal force is sufficiently resisted to impede outward movement of a particle to such an extent that each particle describes a spiral 75 path and is passed over a number of times before discharge from the table.

While I have mentioned 700 to 1000 feet per minute, depending on the character of material, the harder the material the higher 80 the speed, as being a desirable speed for best impact or crushing operation, it is to be understood that by this I mean a minimum speed, at which the best crushing action takes place. Of course, greater impart or kinetic 85 energy would be available at higher speeds; however, at such high speeds centrifugal force acting on the material would become greater and the power required to operate the machine would be increased at a much 90 greater rate with little, if any, increase in capacity. By a speed of 700 to 1000 feet per minute, I mean the best practicable speed at which crushing of materials may be most 95 efficiently accomplished.

I claim:—

1. A pulverizing apparatus comprising a rotating table and pulverizing rollers mounted for rolling thereabove by frictional engagement therewith or with the material thereon, the table having the surface on which the rollers are lodged sloping downward from its circumference toward its center at an angle not exceeding fifteen degrees with respect to the plane of rotation, 100 whereby movement of the material across the table due to centrifugal action is sufficiently retarded to produce maximum crushing, means for mounting the rollers for movement toward and from the table, and means for adjustably loading the rollers whereby a crushing pressure in addition to that due to the weight of the rollers may be had.

2. A pulverizing apparatus comprising a rotating table and pulverizing rollers mounted for rolling thereabove by frictional engagement therewith or with the material thereon, the table having the surface on which the rollers are lodged sloping downward from its circumference toward its 110 center at an angle not exceeding fifteen degrees with respect to the plane of rotation, whereby movement of the material across the table due to centrifugal action is sufficiently retarded to produce maximum crushing, non-rotating axles on which the rollers are mounted for rotation, the axles being pivoted at the outer ends for swinging in vertical planes to carry the rollers toward 120 and from the table, and adjustable means 125

- for biasing the axles so as to exert pressure of the rollers on the table, whereby a crushing pressure in addition to that due to the weight of the rollers may be had.
5. A pulverizer comprising in combination with a fixed support, a rotating table having an annular track which is inclined slightly downward from its periphery toward its center, pulverizing rollers, axles 65 upon which the rollers are journaled free for rotation by frictional engagement with the annular inclined track, whereby nearly the entire weight of the rollers is effective to assist in crushing material on the table, means for adjustably loading the rollers, whereby the bearing pressures thereof on the inclined annular track may be varied, means for delivering material to be treated at the inner ends of the rollers, and means 10 for receiving the pulverized material from the outer edge of the table.
6. In a pulverizing apparatus, the combination of a fixed support, a rotating table having a dished upper surface, means for delivering material to be treated onto the table, means for pulverizing the material on the table, the material having free course over the table toward the circumference, whereby the rotation of the table tends to 15 discharge the pulverized material centrifugally against gravity due to the dished form of the table surface, a discharge-controlling ring encompassing the pulverizing means and having its lower edge overhanging the circumferential margin of the table, and means for adjusting said ring toward and from the table to vary the discharge 20 passage between its lower edge and the table.
7. The construction defined in claim 4 foregoing, the throttling device being a frusto-conical annulus mounted for vertical 25 adjustment on the casing, its inner or lesser diameter being at its upper end and approximating the diameter of the table; the means for mounting and adjusting said annulus being adapted for moving it up and down to carry its height through the horizontal plane of the delivery edge of the upper surface of the table.
8. A pulverizing apparatus comprising, in combination with a fixed supporting structure, a rotating table having a dished upper surface, and rollers for pulverizing material supplied to the table, a tube through which the material is fed onto the table at the inner ends of the rollers and 30 means permitting its delivery off the table at the outer circumference thereof, the table having a central upraise onto which the material is delivered, said upraise having a flat top to a diameter in excess of the diameter of the feed tube, for lodgement thereon of material delivered through the tube in a pile sloping at the angle of repose of the material, said upraise dropping off abruptly from said flat top to a slope at 35 approximately the angle of the repose.
9. A pulverizing apparatus comprising, in combination with a fixed support a rotating table, and pulverizing means arranged above the table for pulverizing material supplied to the latter, a casing encompassing the pulverizing means and extending thereabove, a feed hopper positioned above the pulverizing means at the central part of the table, a feed tube extending from the delivery of the hopper downward and overhanging the table at the center thereof, said feed tube comprising two telescoping members, a horizontal shaft having right-and-left-threaded portions journaled on the hopper, threaded sleeves on the said threaded portions respectively, and links from said sleeves to the lower and outer telescoping member of the tube, said shaft being extended out through the casing for exterior access to rotate it to raise and lower said lower telescoping member.
10. In testimony whereof, I have hereunto set my hand at Chicago, this 7th day of February, 1921.

OTTO A. KREUTZBERG.
